DESIGN FOR A BOTTLE

Paul Plunkett, Greenwich, Conn., assignor to
Moulded Pulp Corporation, Dover, Del., a cor-
poration of Delaware

Application September 22, 1934, Serial No. 53,372

Term of patent 14 years

To all whom it may concern:

Be it known that I, Paul Plunkett, a citizen of the United States, residing at Ritch Avenue, Greenwich, county of Fairfield and State of Connecticut, have invented a new, original, and ornamental Design for Bottle, of which the following is a specification, reference being had to the accompanying drawing, forming a part thereof.

Fig. 1 is a top plan view of a bottle;
Fig. 2 is a front elevation; and

Fig. 3 is a fragmentary bottom perspective view thereof.

The drawing shows a bottle, the dominant feature of which is its shape, and the subordinate feature of which is the roughened or pimpled appearance of the surface.

I claim:

The ornamental design for a bottle as shown and described.

PAUL PLUNKETT.
